A. F. TONKEL

LIQUID DISPENSING APPARATUS

Filed March 10, 1927

INVENTOR
Albert F. Vonkoh
BY
Walter A. Knight
his ATTORNEY

UNITED STATES PATENT OFFICE.

ALBERT F. TONKEL, OF FORT WAYNE, INDIANA, ASSIGNOR TO WAYNE COMPANY, OF FORT WAYNE, INDIANA, A CORPORATION OF INDIANA.

LIQUID-DISPENSING APPARATUS.

Application filed March 10, 1927. Serial No. 174,178.

My invention relates to liquid measuring and dispensing apparatus of the so-called visible type, having a transparent elevated reservoir into which extends a vertically adjustable tube; and particularly to such apparatus equipped with positive quantity stop mechanism.

In some of this visible apparatus the vertically adjustable tube is on the drain-back side of the apparatus, that is, it is adapted to return some of the liquid in the elevated container to the storage tank, and what remains in the elevated container is served to the customer; while in others the vertically adjustable tube is on the serve side of the apparatus, that is, it is adapted to convey liquid from the elevated container through the serve outlet to the customer. My invention is applicable to either type and any form thereof, whether hand or power operated, having a rotating shaft for raising and lowering the tube.

The principal object of my invention is to provide means for preventing change of the position of the vertically adjustable tube while the serve valve is open, thus ensuring honest measurement of the liquid dispensed.

The particular embodiment of my invention selected for illustration is applied to a visible dispensing apparatus having the vertically adjustable tube on the overflow side.

Figure 1 is an elevation of such an apparatus, the upper part of the casing and the lower part of the elevated container and top-head being broken away and in section to show that portion of the mechanism which embodies the invention. The upper part of the fill-tube is also broken away. The serve-valve is closed.

Fig. 2, an enlarged detail, is the clutch-throwing mechanism in the casing, shown in the position it takes when the serve-valve is open.

Fig. 3 is a cross-section on the line 3—3 of Fig. 2.

Fig. 4, a detail, is a section on the line 4—4 of Fig. 2.

Fig. 5, a detail, is a section on line 5—5 of Fig. 2, and

Fig. 6, a detail, is a top plan view of the cross head used in adjusting the vertical height of the tube N.

Referring now to the drawings, A is a casing housing the general operating mechanism, with pedestal α at the bottom and

cylindrical glass container C above resting on the bottom-head c , which in turn is seated upon and secured to the casing A. A cover c^1 surmounts the container C, and through an opening c^2 in the bottom-head c the gasoline flows to the pipe v and thence through the valve V to the serve hose Y when the valve-lever v^1 is raised. The valve is closed in the position shown in Figure 1.

The valve-lever v^1 and the throw-out lever v^2 are both rotatively fixed to the valve rod v^3 so that when the valve-lever v^1 is raised the throw-out lever v^2 is raised also, and through the connecting rod d rotates the cam D, pivoted at d^1 to the shifter-rod d^2 , to the other end of which is secured a fork d^3 seated in the peripheral groove of a clutch d^4 , rotatably secured to the shaft E by spline e , said clutch d^4 being normally held in contact with the clutch-teeth e^2 of the gear e^1 by spring S.

Gear e^1 is free to rotate on the shaft E, but when rotatably secured thereto by means of the clutch members d^4 , e^2 it raises or lowers the rack R with which it is constantly in mesh.

A suitable bearing plate F is secured to the casing A and on one end of it is formed a cylindrical boss f bored to form a bearing for the shaft E, and on its other end is formed a bearing for the shaft of the roll f^1 , which presses against the back of the rack R keeping it pressed forward into constant meshing contact with the gear e^1 .

A bearing block G is secured by a clamp g and bolts g^1 , g^2 to the fill pipe B, which extends upwardly into the visible container, and through which the liquid to be dispensed is delivered thereto. The bearing block G is drilled to form bearings for the shafts d^2 and E, heretofore described, and against the end of this bearing block the cam D bears when rotated into the position shown in Fig. 2.

A conduit through which liquid is drained from the elevated container C back to the storage tank (not shown) consists of an upper portion M, a connecting portion M^1 and a lower portion M^2 . A vertically adjustable tube N, open at both ends, is adapted to be raised and lowered, the upper end always remaining in the elevated container C and the lower end always remaining in the upper portion M of the drain-back conduit. Vertical movement of the tube N is effected

through the rod n , the upper end of which is secured to the lower end of the tube N , and the lower end of the rod n is secured to a cross-head H , guided by rod h operating 5 through guide lugs r secured to the rack R . The rod h is secured at its top and bottom to the casing or other fixed parts of the apparatus. The rod n passes through any suitable stuffing-box (not shown) in the bottom 10 of the connecting portion M^1 . The rack is secured at its lower end to the cross-head H so that upon rotation of the crank e^3 , when the clutch elements e^2, d^4 are in mesh, it will raise or lower rack R , cross-head H , rod n 15 and tube N . When the clutch elements are disengaged rotation of the crank e^3 does not raise or lower the tube N or rack R . The clutch elements are always disengaged when the serve valve V is open, that is, when the 20 serve-valve lever v^1 is in raised position.

Stop mechanism of any suitable kind may be used. That shown and designated as T on the drawings and particularly in Fig. 1 is the subject of pending application of 25 William F. Brandt, Serial No. 184,664 filed Apr. 18, 1927.

I do not limit myself to the mechanism herein shown but claim as within the scope of my invention any apparatus readable on 30 the claims.

I claim as my invention and desire to secure by Letters Patent of the United States:—

1. In a liquid dispensing apparatus having 35 an elevated liquid container, a serve outlet from said container and a valve therefor, a vertically adjustable tube extending from below into said container, a shaft and shaft-actuated means for raising and lowering 40 said tube, and means operable by opening

of said valve for disengaging said tube-actuating means until the valve is closed.

2. In a liquid dispensing apparatus having an elevated liquid container, a serve outlet from said container and a normally closed 45 valve therefor, means for opening said valve, a vertically adjustable tube extending into said container, a rotating shaft, a rack secured to said tube to raise and lower it, a loose gear on said shaft in mesh with said rack, a clutch, one member of which is rotatably secured to the shaft and the other to the contiguous face of the gear, means for normally holding said clutch elements in operative relation to each other, and means 55 operable by opening said valve for disengaging said clutch.

3. In a liquid dispensing apparatus having an elevated liquid container, a serve outlet from said container and a normally closed 60 valve therefor, means for opening said valve, a vertically adjustable tube extending into said container, a rotating shaft, a rack secured to said tube to raise and lower it, a loose gear on said shaft in mesh with said rack, a clutch, one member of which is rotatably secured to the shaft and the other to the contiguous face of the gear, means for normally holding said clutch elements in operative relation to each other, a cam adapted 65 to its rotation to disengage said clutch elements, and connecting means between said cam and said valve-opening means whereby upon the opening of said valve said cam will be rotated and the clutch elements disengaged. 70

In testimony whereof I have hereunto set my hand.

ALBERT F. TONKEL.
